UNITED STATES PATENT OFFICE

WILLIAM S. GUBELMANN, OF BUFFALO, NEW YORK

WORD-PRINTING MECHANISM

Original application filed January 10, 1900, Serial No. 1,004. Divided and this application filed August 28, 1918. Serial No. 251,778.

The present invention relates particularly to word printing mechanism that is intended for use in calculating machines, cash registers and like machines; and is a division of my application Serial No. 1,004, filed January 10, 1900, and eventuating in Patent No. 1,429,201, dated September 12, 1922.

One of the objects of the invention is to provide improved means for printing words in conjunction with the printing of items by one or a plurality of sets of types which may be associated with one or a plurality of sets of accumulators.

Another object is to provide means for printing words in conjunction with the printing of a total by an item-printing mechanism under control of an accumulating mechanism.

Another object is to provide word types which are mounted to be separately movable on a common type sector.

Other objects will be pointed out in the following description and claims.

The mechanism whereby the above objects are attained is illustrated in the accompanying drawings consisting of seven sheets, in which:

Figure 1 is a fragmentary top plan view of my improved adding and recording machine.

Figure 2 is a vertical longitudinal section of the same, taken substantially in line 2—2, Figure 1, and showing the adding and recording mechanism of one column or set of keys in the normal or inoperative position.

Figure 3 is a fragmentary sectional elevation of the printing mechanism of one of the rows of keys viewed from the side opposite to that shown in Figure 2.

Figure 4 is a fragmentary perspective view of the units gear segment and controlling arm of the main adding mechanism.

Figure 5 is a horizontal section in line 5—5, Figure 3.

Figure 6 is a vertical section in line 6—6, Figure 3.

Figure 7 is a fragmentary longitudinal sectional elevation taken substantially in line 7—7, Figure 1, and showing the auxiliary adding and recording mechanism.

Figure 8 is a fragmentary longitudinal sectional elevation taken substantially in line

8—8, Figure 1, and showing the mechanism whereby words are printed.

Figure 9 is a longitudinal sectional elevation, taken substantially in line 9—9, Figure 1, and showing particularly the paper carriage and the mechanism whereby different parts of the machine may be thrown into and out of gear.

Figure 10 is a fragmentary perspective view, showing the key lever, the main gear segment, the controlling arm and the printing segment of one of the higher columns of numbers.

Figure 11 is a fragmentary transverse section taken in line 11—11, Figure 2, and showing means for adjusting the paper carriage lengthwise of the line of printing.

Figure 12 is a vertical section taken substantially in line 12—12, Figure 2.

Figure 13 is a vertical transverse section taken in line 13—13, Figure 2.

Figure 14 is a fragmentary transverse sectional elevation taken in line 14—14, Figure 2, and shows the mechanism for holding the keys in their depressed position and for releasing the same.

Figure 15 is a fragmentary sectional side elevation of one of the printing segments showing the means for mounting the type movably thereon.

Figure 16 is a cross section of the type segment taken in line 16—16, Figure 15.

Figure 17 is a side view of one of the type-carriers viewed from the side opposite to that shown in Figure 15.

Figure 18 is a perspective view showing one of a pair of substantially similar cams, one of which serves to shift the main dial operating segments into their operative position and the other one of which serves to shift the parts into position for printing a total of the added numbers.

Figure 19 is a fragmentary perspective view of the hammer operating mechanism.

Like letters of reference refer to like parts in the several figures.

General adding and printing mechanism

The reference numeral 40 (Figs. 1 and 2) denotes numeral keys arranged in denomina-

55

60

65

70

75

90

100

tional rows and depressible to set up items or amounts for entry into a series of accumulator wheels 2 (Fig. 2). Each row of numeral keys has associated therewith a key lever 36, 37, the vertical arm 37 of which is provided with a series of stop shoulders 39 and the horizontal arm 36 of which extends below the corresponding row of keys for operation by any key in said row. Also associated with each row of keys is a corresponding one of a series of controlling arms 30 pivoted on a cross rod 31 and cooperating with the related key lever 36, 37. Normally each controlling arm stands in the position shown in Fig. 2, wherein a lug 33 on said arm is engaged by shoulder 38 on the rear side of the arm 37 of the associated key lever. Upon depression of any numeral key in the corresponding row, the key lever is turned, disengaging said shoulder 38 from lug 33 of said controlling arm and bringing into the path of a lug 34 on said arm a stop shoulder 39 corresponding to the key depressed. Upon then operating the machine by drawing forwardly the operating lever 21 (Fig. 12) said controlling arm is drawn downwardly until stopped by the engagement of its lug 34 with that stop shoulder 39 that has been positioned in its path.

Connected with each controlling arm through lugs 46 and 50 is a toothed segment 5 adapted to engage and actuate a corresponding one of a series of pinions 4 attached to the respective accumulator wheels 2. The segments 5 are shiftable forwardly and rearwardly with respect to the controlling arms for engagement with and disengagement from the respective pinions 4. Also connected with each controlling arm 30 is a corresponding one of a series of type segments 141 each provided with a set of numeral type elements 142. It will thus be seen that the positions to which the actuating segments 5 and printing segments 141 are movable are controlled by the arms 30, in conjunction with the respective key levers; the latter, in turn, being settable by the numeral keys.

The operating handle 21 is secured to one end of the shaft 20 (Figs. 2, 7, and 12), to which shaft a frame 15 (Figs. 2 and 12) and a frame 29 (Figs. 9 and 12) are attached. During the initial forward rocking of said handle 21 the frame 15, through its attached cam plate 14 acting upon arm 13, rock arms 8, and rod 7, throws the actuating segments 5 into mesh with the respective accumulator pinions 4. As forward rocking of said handle 21 continues, the rear walls of notches 28 in the frames 15 and 29 come into engagement with a cross bar 25 carried by rock arms 24 loosely mounted on shaft 20, and rock said bar 25 downwardly and forwardly. Such lowering of said bar 25 moves downwardly a cross rod 22 connected thereto and underly-

ing the segments 5, and also exerts a downward pull upon springs 27 connecting said bar 25 and said segments. Thereby, those segments 5 whose controlling arms 30 have been freed by depression of numeral keys are moved downwardly, together with their controlling arms, through extents commensurate with the setting of the key levers; and the accumulator pinions 4 are turned by said segments through corresponding extents whereby the amount set up on the key board is added to the sum formerly standing upon said wheels. Also, the segments 141 are moved with said controlling arms and bring to the printing line type corresponding to the depressed keys.

After the type segments 141 have been positioned as aforesaid, hammers 147 are actuated to drive rearwardly the respective type elements 142 that are in printing position whereby the amount set up by the numeral keys is printed on a record sheet carried by a platen 140. Operation of the hammers 147 is caused by the drawing downwardly of a bar 151 supported by arms 152 from rod 31 and carrying a series of pawls 153 (Figs. 2, 3, 6 and 19), one for each hammer. During the setting of the printing segments to their proper positions the pawls 153 corresponding to those of the hammers 147 that should be operated for printing the item are moved into operative relation with said hammers, each of said pawls engaging a shoulder 156 on its related hammer; and upon the ensuing rocking of the bar 151 said hammers are drawn downwardly by said pawls. During such movement of said hammers an upper lug 157 (Fig. 3) on each hammer engages a trip face 155 on the associated pawl and cams the latter out of engagement with the lug 156, whereby said hammers are released and are driven rearwardly by their springs 148 to effect printing by the type elements 142 that are at the printing line. The operation of the rod 151 to cause actuation of the hammers is effected through a hook 168 connected to said rod and engageable by a cross rod 169 carried by the rock arms 24 above mentioned.

At or near the end of the forward movement of the operating handle 21, the cam 14 on frame 15 moves clear of the roller 18 on arm 13, whereupon spring 11 (Fig. 9) draws arms 8 backwardly to their position shown in Fig. 2. During the rearward or return rocking of handle 21, the shaft 20 and frames 15 and 29 rock rearwardly, the arms 24 are rocked to raise the lifting rod 22, and the actuators 5, controlling arms 30, and printing segments 141 are restored to their normal position.

For a more detailed description of the operations of accumulating and printing reference may be made to the parent case (Patent No. 1,429,201) hereinbefore referred to.

Word-printing mechanism

For the purpose of permitting words to be printed in front of the numbers which are added together, the following mechanism is provided:

1411 (Figs. 1, 8, 12 and 13) represents a word-printing segment which is mounted loosely on the rod 31 next to the highest number-printing segment of the main number-recording mechanism. This segment is provided with a number of radially movable carriers 1420, which are constructed the same as the carriers of the number printing segments and each of which is provided on its face with a word-type. The words of these types are selected according to the purpose or business for which the machine is to be used. For instance, if the machine is to be used in a bank, types representing the words "Vouchers", "Checks", "Drafts", "Bills", and similar words, common to the banking business may be used. When the machine is designed for use in a restaurant, the words "Soup", "Vegetables", "Meats", "Dessert", and other words peculiar to this business may be used.

The position of the word-type segment is controlled by a key-lever 3600, Figure 8, which turns on the bar 35, is similar to the number key levers, and is provided on the front side of its upper arm 3700 with a vertical series of differential stops or shoulders 3900 which are adapted to be engaged by the stop-lug 3400 of a controlling arm 3000; and lever 3600 is also provided with a locking stop or shoulder which is adapted to be engaged by a locking lug 3300 on the controlling arm, as represented in Figure 8. The controlling arm 3000 is connected with the word-printing segment by a connecting-bar 1460. The stop-shoulders on the upper arm of the word-key lever are so arranged that upon swinging this lever so as to carry different shoulders into the path of the stop lug on the controlling arm, the latter will be arrested at different points in its downward or forward movement and the word-printing segment connected therewith will be stopped at different points in its upward movement and present the particular word-type to the printing point which corresponds with the shoulder or stop on the word-key lever.

The upward movement of the controlling arm 3000 is limited by its rear locking lug 3300 engaging with the stop-bar 32, which arrests the upward movement of the controlling arms 30 of the number registering and recording mechanism. The downward movement of the controlling arm 3000 and the simultaneous upward movement of the word-printing segment is effected by a spring 215 which yieldingly connects this arm with the bar 25 to which the registering gear segments are connected.

216, Figure 1, represents a row of word-keys having depending stems which are

guided in the top and bottom of the key-board and which engage against the upper side of the front arm 3600 of the word-key lever at different distances from the fulcrum thereof. Upon depressing any of the word-keys, the word-key lever will be turned the proper distance to bring its proper stop shoulder into the path of the stop lug of the companion controlling arm and arrest the word-type segment during its upward movement, when the word-type corresponding with the word of the depressed key has reached the printing line. When the respective word-type is in this position the same is driven against the recording surface for producing an impression thereon, at the same time that the printing of the numbers by the numbering printing segments is effected. The word-types are driven against the platen by a hammer-operating mechanism which is constructed the same as the hammer-operating devices of the number printing mechanism and the same letters of reference are therefore used to denote the same. The word-key lever is yieldingly held in its normal position by a spring 600 (Fig. 8).

Auxiliary adding mechanism

An auxiliary adding mechanism is provided which permits of effecting an addition of numbers different from the numbers which are added by the main adding mechanism.

This auxiliary adding mechanism is constructed as follows:

2000 (Fig. 7) represents a number of auxiliary dials which are mounted on the left hand end of the dial shaft 3.

5000 represents a number of auxiliary gear segments which are mounted on the transverse rod 7, and are adapted to engage with gear pinions 400 on the auxiliary dials, as represented in Figure 7. Each gear segment 5000 is connected with a controlling arm 3001 arranged adjacent to the gear segment by a latch or coupling which at times permits the segment to move independently of the controlling arm.

3601 and 3701 represent auxiliary key levers which are operated by auxiliary keys 401 and which control the operation of the auxiliary registering and recording mechanism. The detail construction of the dials, gear segments, printing segments, key levers and the parts co-operating therewith of the auxiliary registering and recording mechanism is substantially the same as the construction of the same parts in the main registering and recording mechanism, except as hereinafter distinguished, and the same letters of reference are therefore employed to denote like parts in both of these sets of mechanisms.

In the drawings, two auxiliary key levers and three auxiliary dials are shown, which permits of registering and recording a total of 999, but additional registering and record-

ing devices may be employed if it is desired to increase the capacity of the machine.

In the auxiliary mechanism each of the higher gear segments 5000 is provided with a pivot latch (Fig. 1) the same as latch 50 in the main registering mechanism. The lowest or primary gear segment of the auxiliary registering mechanism is provided with a movable latch 502 (Fig. 7) which is adapted to be engaged with or to be disengaged from the upper guide face on its companion controlling arm, but for the purpose of the present application this latch might be dispensed with and the primary gear segment constructed the same as the primary gear segment of the main registering and recording device.

In the auxiliary registering mechanism the gear segments are not provided with lower stops 46 like those of the gear segments of the main registering mechanism which permits the auxiliary controlling arms to move downwardly when necessary independently of the auxiliary gear segments. The upward movement of the auxiliary gear segments is limited by stops 218 with which the upper ends of the gear segments engage. 219 represents a foot formed on the lower side of each controlling arm 3001 and adapted to engage with the lifting cross-bar 22. However, for the purpose of the present application, the auxiliary mechanism could be made exactly as the main number registering and recording mechanism is made.

For the purpose of effecting an ordinary addition of numbers on the auxiliary registering mechanism, the auxiliary key levers are shifted into the proper position by the depression of the keys 401 representing the numbers to be added and then the rocking segments 15 and 29 are turned forwardly. During the forward movement of the rocking frames the auxiliary gear segments are first moved into engagement with the auxiliary dial pinions by the cam 14 and then pulled down by the springs 27, and the controlling arms are also pulled down by the latches of the gear segments engaging with the controlling arms. The downward movement of the gear segments and controlling arms continues until the stops 34 of the controlling arm strike the shoulders 39 on the key levers which stand in the path of the stops 34. At the end of the forward movement of the rocking frames the gear segments are withdrawn from the dial pinions by the springs 11 and during the subsequent backward movement of the rocking frames the gear segments and controlling arms are raised by the cross-bar 22 engaging with the gear segments and with the feet 219 of the arms. The carrying of numbers from the units dial to the tens dial and from the latter to the hundreds dial and the turning of the dials

to zero is effected in the same manner as in the main registering mechanism.

By this organization of the machine, numbers such as sales or pieces of goods can be added and recorded by the main registering mechanism and other numbers such as the rebate on sales and discount on the prices of the goods, can be separately added or recorded by the auxiliary registering mechanism.

The key-controlled devices whereby the parts of the main registering and recording mechanism are shifted into the proper position preparatory to registering and recording a number are distinct from the key-controlled devices whereby the same effect is produced in the auxiliary registering and recording mechanism, but both sets of registering and recording mechanisms are operated simultaneously by the one universal shifting mechanism for effecting the registration and recording of the numbers which are represented by the different positions of both key-controlled devices.

Indicator or detector dials

In order to enable the operator to see which particular character or characters the machine is set for printing after depressing the keys, and thereby detect any errors in the depression of the keys, each of the key levers is provided with an auxiliary dial indicator or detector, 238, which is turned forward the same number of spaces that the key lever has been depressed and then returns to its initial position when the key lever moves backward into its normal position. In the preferred construction of the detector dials shown in Figures 1, 2, and 8, each of these dials consists preferably of a wheel 238 provided on one side with a pinion 239 which is engaged by a gear segment 240, secured to the adjacent key-lever, as shown in Figure 2.

Upon depressing one of the number-registering and recording keys, the detector dial thereof is turned forwardly by the connecting gearing the same number of spaces corresponding with the number of the key which has been depressed. If a key lever is not depressed its detector dial remains at zero. The detector dial of the word-printing mechanism is in like manner turned by its key lever so as to indicate the word which corresponds to the word of the depressed key.

The detector dials of the several registering and recording devices are mounted loosely on a transverse supporting rod 241. By means of these detector dials the operator can see which number and word is represented by the depressed keys, thereby enabling the same to be corrected if an error occurs before registering and printing the same.

The type are driven by the means hereto-

fore described against a record sheet which passes in front of a rotatable platen 140, which may be supported in a horizontally movable carriage, and line spaced at each operation of the machine, or rotated by hand to a desired position. Suitable means for inking the type are also provided, all as more fully described in Patent #1,429,201 and in Patent #1,590,024, dated June 22, 1926.

10. Suitable means are provided for latching down the depressed keys (except the totalizer clearing key), for automatically releasing the keys at the proper time in the operation of the machine, and for manually releasing 15 shifting keys, or numeral keys that have been wrongly depressed. A device is likewise provided for insuring a full stroke of the operating handle after its displacement from home position. Mechanisms for these purposes are fully described in Patent #1,429,201 and in applications, Serial Nos. 183,397, and 20 183,398, filed July 30, 1917.

The two columns or rows of word and shifting keys are each provided with a locking 25 mechanism similar to the main and auxiliary keys, but the locking plates of these keys are disengaged from the stems by a separate releasing mechanism so as to permit the main and auxiliary number keys to be released 30 without releasing the word and shifting keys.

As shown in Figure 14, the release of the word and shifting keys is effected by a supplemental releasing bar 348 having lugs 349 which engage with the pins 335 on the rear 35 end of the locking plates of the word and shifting keys and which is guided at its outer end in the frame. The inner end of the supplemental releasing bar is pivoted to the upper arm of a releasing elbow lever 350. This 40 lever is pivoted on the pin 337 and its lower arm projects toward the right and underneath the releasing arm 338 adjacent to the rear side of the lower arm of the releasing elbow lever 336.

45. When both lower arms of the releasing elbow levers 336 and 350 are arranged underneath the releasing arm 338, the depression of the latter by the rocking frames causes the supplemental releasing bar to be moved 50 toward the left so that its lugs disengage the locking plates of the word and shifting keys from their respective stems at the same time that the main and auxiliary releasing bars disengage the locking plates of the main and 55 auxiliary number keys from their respective stems, thereby releasing all of the keys simultaneously after the registering and recording of the words and numbers has been effected.

The invention is not limited to the precise 60 mechanism which has been illustrated and described but extends to all equivalent devices falling within a broad interpretation of the appended claims.

What is claimed is:

65. 1. In a machine of the class described, the

combination with word-printing mechanism employing a platen, of mechanism separate from the word-printing mechanism operable to print numbers on the said platen, and means for concomitantly accumulating a plurality of separate totals of the numbers as recorded when so required and simultaneously recording said totals on said platen; substantially as described. 70

2. In a machine of the class described, the combination with word-printing mechanism having a platen arranged to carry paper, of devices carrying number type independent of the word-printing mechanism, means for making a printing impression, and a number 80 of separate totalizers operable to produce separate totals of the distinctive items recorded and adapted to control the simultaneous recording of said totals on said platen; substantially as described. 85

3. In a machine of the class described, the combination with word-printing mechanism employing a platen arranged to carry paper, of devices carrying type independent of the word-printing mechanism, means for printing the numbers by use of the type, means for concomitantly retaining a plurality of separate totals of the distinctive items recorded, and means for simultaneously recording said separate totals on said platen; substantially as described. 90 95

4. In a machine of the class described, the combination with word-printing mechanism having a platen arranged to carry paper, of devices carrying number type independent of the word-printing mechanism, independent hammers operable to drive the type in the carriers against the platen, and total wheels operable to add the numbers recorded, and means for recording said totals on 105 said platen, substantially as described. 100

5. In a machine of the class described, the combination with a totalizer, racks, type positioned by said racks some of whose printing type are always in printing position, independently operable type-hammers for said type, a platen for supporting paper and separate mechanism for printing words adjacent to and in line with said first-mentioned printing type; substantially as described. 110 115

6. In a calculating machine, the combination of a set of accumulators operable to accumulate items, a plurality of numeral printing types operable for printing items accumulated on said set of accumulators, driving mechanism for driving predetermined ones of said types toward for printing on a record sheet, a plurality of special printing types operable to print matter other than numerals on said record sheet and in juxtaposition to the items printed by said numeral printing types, driving mechanism other than the first said driving mechanism for driving predetermined ones of said special types toward said record sheet for printing thereon, and operat- 120 125 130

ing mechanism common to for operating both of said driving mechanisms.

7. In a calculating machine, the combination with a plurality of accumulators for accumulating items; of a plurality of sets of numeral types, one set for each denomination of said accumulators; a platen co-operative with said types, a carriage upon which said platen is mounted, and which is operable to move said platen transversely of said types for receiving impressions therefrom in different columnar positions; a plurality of special types co-operative with said platen to effect printing of matter other than numerals; and a plurality of sets of keys, the keys of one set being constructed to control when depressed, the printing of numbers by said numeral printing types, and the keys of the other set to control printing by said special types.

8. In a calculating machine comprising a print receiving platen and a carriage upon which said platen is mounted and which is operable to move said platen transversely of said types, the combination of a plurality of accumulators for accumulating items; a plurality of sets of numeral types, one set for each denomination of said accumulators; a hand-controlled operation-controlling member operable at a single operation to cause a plurality of said accumulators to accumulate and to cause printing by a type of each of a plurality of said sets of numeral types; a plurality of special types co-operative with said platen to effect printing of matter other than numerals; and a common key-board, comprising a plurality of rows of number keys, one row for each accumulator and set of numeral types of a plurality of said accumulators and sets of numeral types, and a set of keys for controlling said special printing types.

9. In a calculating machine, the combination of a plurality of sets of accumulators, each set of a plurality of said sets being operable to accumulate a series of items which may be different from the series of items accumulated by another of said sets of accumulators; a plurality of sets of numeral printing types, one set of numeral printing types for each of a plurality of said sets of accumulators for printing items accumulated thereby; a plurality of special types operable to print matter other than numerals; a platen common to said numeral and special types and operable to back a record sheet to be printed on thereby; and operating mechanism common to and for effecting operation of a plurality of said sets of accumulators and a plurality of said sets of numeral printing types and of said special types.

10. In a calculating machine, the combination of a plurality of sets of accumulators, each set of a plurality of said sets being operable to accumulate a series of items which

may be different from the series of items accumulated by another of said sets of accumulators; a plurality of sets of numeral printing types, one set of numeral printing types for each of a plurality of said sets of accumulators for printing items accumulated thereby; a plurality of sets of manipulative controlling members associated respectively with said sets of accumulators and their printing type, a plurality of special types operable for printing matter other than numerals; a plurality of manipulative members operable for controlling which of said special types shall print; a platen common to said numeral and special types and operable to back a record sheet to be printed on thereby; and operating mechanism common to for effecting operation of a plurality of said sets of accumulators and a plurality of said sets of numeral printing types according to the control of said plurality of sets of manipulative members and for effecting printing by said special types according to the control of the respective manipulative members.

11. In a calculating machine, the combination of a plurality of accumulators operable to accumulate items; a plurality of keys for determining the items to be accumulated by said accumulators; printing mechanism comprising a plurality of numeral types operable to print items accumulated by said accumulators and also comprising a plurality of special types for printing matter other than numerals in juxtaposition to said items; a total key; and operating mechanism operable at a single operation to cause printing of a total from said accumulators under control of said total key and said accumulators and to cause printing of identifying matter by special types and in juxtaposition to the total printed.

12. The combination of numeral printing devices arranged side by side, a printing device for printing matter other than numerals and in conjunction with numerals printed by said numeral printing devices, numeral setting keys for controlling the operation of said numeral printing devices, setting keys for controlling the operation of the second said printing device, a common operating mechanism for operating said printing devices according to the control of their respective setting keys, and flexible connecting mechanism for connecting said printing devices and said operating mechanism.

13. In a calculating machine comprising a plurality of numeral printing types and a plurality of types for printing characters other than numerals in conjunction with the numerals printed by said numeral printing types, in combination, a segment for carrying said character types, means for moving said segment to bring different ones of said character types to printing position, a dit.

- ferential stop member for limiting the movement of said segment by said means, and keys for controlling said differential stop member.
- 5 14. In a machine comprising a horizontally movable carriage, means on said carriage for carrying and line spacing a record sheet, and means for detaining said carriage in a position for locating the printing in a predetermined position on said record sheet and operable for allowing said carriage to be moved to a position for continuing said printing in another space; in combination, an operating member, a set of numeral types 70
- 10 a plurality of which may be impressed by a single operation of said operating member so as to print numerals on said record sheet, and a set of word printing types for printing words on said record sheet in connection 75
- 15 with said numerals.
- 16 15. The combination with a main item registering and recording mechanism and its key-controlling operating mechanism, a word recording mechanism and its key-controlled 80
- 20 operating mechanism, and an auxiliary item registering and recording mechanism and its key-controlled operating mechanism, of a universal actuating mechanism whereby said operating mechanisms are shifted, substantially as set forth.
- 25 16. In a calculating machine, the combination of a set of accumulators operable to accumulate items into totals, a plurality of numeral types operable for printing items 85
- 30 accumulated by said accumulators, a plurality of keys for determining said items, universal operating mechanism for causing said accumulators to accumulate and said numeral types to print the items determined by said 90
- 35 keys and operable for effecting printing by said numeral types of the total accumulated by said accumulators and under control of said accumulators, a plurality of special types optionally operable for effecting printing of 95
- 40 matter other than numerals in juxtaposition to items and totals printed by said numeral types, and a plurality of manipulative members for controlling printing by said special types.
- 45 17. In a calculating machine, the combination of a set of accumulators operable to accumulate items into totals, a plurality of numeral types operable for printing items and tools accumulated on said accumulators, 100
- 50 a plurality of keys for determining said items, a plurality of special types operable for effecting printing of matter other than numerals in juxtaposition to items and totals printed by said numeral types, a plurality of manipulative members for controlling printing by said special types, and universal operating mechanism for causing said accumulators to accumulate and said numeral types to print the items determined by said keys 105
- 55 and operable for effecting printing by said 110
18. In a machine of the character described, the combination of a differentially reciprocatory special type carrier having an abutment projection; a step indexing member movable to present one or another of its shoulders in the path of said projection; and special keys and connections for variously positioning said indexing member.
19. In a machine of the class described, the combination of number printing mechanism, a totalizer adapted to receive items printed by said number printing mechanism, means for causing said number printing mechanism to print totals of said items under control of said totalizer, and mechanism for printing words in conjunction with said totals for identifying the latter.
20. In a machine of the class described, the combination of number printing mechanism, a totalizer adapted to receive items printed by said number printing mechanism, means for causing said number printing mechanism to print totals of said items under control of said totalizer and mechanism adapted to print words in conjunction with the items 95
21. In a machine of the class described, the combination of a platen for carrying a record sheet, means for printing items on said record sheet, a totalizer for receiving said items, means for causing totals of the items to be printed on said record sheet under control of said totalizer, and means for printing words on said record sheet for identifying the items.
22. The combination of a plurality of word printing types, a segment supporting said types and movable to bring each of said types to printing position, a series of stops for controlling the position of said segment, a series 110
23. The combination of a plurality of word printing types, a segment supporting said types and movable to bring each of said types to printing position, a member provided with a series of stop elements for controlling the position of said segment, a series of keys for selectively controlling said member to bring a selected stop element into operative relation with said segment, and means for moving said segment to a position determined by the selected element.

WILLIAM S. GUBELMANN.
